Des. 201,404
Patented June 15, 1965

201,404

AIRMAIL ENVELOPE

Rodolfo B. Antelo, 68-02 Dartmouth St.,
Forest Hills 75, N.Y.

Filed Oct. 9, 1963, Ser. No. 76,917

Term of patent 14 years

(Cl. D59—8)

Fig. 1

Fig. 2

FIGURE 1 is a front elevational view of an airmail envelope embodying my new design; and

FIGURE 2 is a rear elevational view thereof.

The dominant features of my design reside in the portion shown in full lines.

I claim:

The ornamental design for an airmail envelope, as shown and described.
